UNITED STATES PATENT OFFICE

JOHN FIELDING, OF NORTH PROVIDENCE, RHODE ISLAND, ASSIGNOR OF ONE-HALF TO
JOSEPH P. WHITAKER, OF APPONAUG, RHODE ISLAND

MEANS FOR SECURING A METALLIC BRIDGE TO METALLIC LENS RIMS

Application filed April 8, 1931. Serial No. 528,614.

This invention relates to an ophthalmic mounting, and has for its object to connect a spring bridge piece to the lens rim without subjecting the same to heat in such connection.

Another object of the invention is the provision of a construction by which a better grade spring may be used and a better connecting member for attaching the spring to the lens rim.

A further object of the invention is the provision of a construction which will be less expensive for joining the spring to the lens rim.

Still further object is the provision of a construction which will provide an improved appearance when viewed from the front thereof.

With these and other objects in view, the invention consists of certain novel features of construction, as will be more fully described, and particularly pointed out in the appended claims.

In the accompanying drawing:

Fig. 1 is a face view of a pair of lens rims connected by my improved bridge mounting means;

Fig. 2 is a top edge view thereof;

Fig. 3 is a perspective view of the spring;

Fig. 4 is a perspective view of one of the connecting members;

Fig. 5 is a central sectional view through the spring and connecting member and lens rim;

Fig. 6 is a section on line 6-6 of Figure 5.

In ophthalmic mountings, it is frequently desirable to attach a flat leaf spring to lens rims, which has been accomplished by soldering the ends of a spring to connections to the lens rim by which the application of soldering heat anneals the spring to detrimentally affect the same. Connecting members have been made integral with the ends of the springs for attachment to the lens rim, but it is found that the connecting members must be of a far more ductile and pliable material than the spring member in order that the same may be attached by bending, folding or the like without the use

of heat, and thus a material must be used which is inferior for spring qualities; and in order to overcome these difficulties, I have provided a construction by which the highest grade spring may be used and which may be attached to the lens rim without the use of heat; and the following is a detailed description of the present embodiment of this invention, illustrating the preferred means by which these advantageous results may be accomplished.

With reference to the drawing, 10 designates the lenses surrounded by rims 11, in this illustration being preferably metallic. Connecting members 12 in the form of soft, pliable, ductile material of flattened tubular form are soldered to the rims 11, and a leaf spring 13 of relatively hard, resilient stock is provided for the bridge with recesses or holes 14 in its opposite ends which are tapered slightly as at 15 for insertion into the tubular sleeve 12 to abut against the closed end 18 thereof. The ends of the spring 13 are held against the closed end 18 of the member 12 by deflection of the metal of the rims 11 and the sleeve 12 by forcing the same inwardly to provide a projection or detent 16 from the stock of the sleeve extending into the recess 14 or through the hole therein where one is provided as illustrated in Figure 5, to lock the end of the spring in the sleeve and connect the rims together. A suitable gauge, to locate the point of application of pressure 17 for deflecting the stock of the rim 11 is provided.

In this manner, the resilient bridge of hard sheet stock is secured to the lens rims without the use of solder and without the necessity of bending any of the hardened stock which is liable to break or crack and be weakened and by which the connecting means is invisible from the face of the mounting to improve the appearance of the construction thereof.

The spring bridge used is of a degree of hardness and flexibility to permit the lens rims to fold or be moved one over the other for more compact storage of the parts and thus it will be apparent that a set may occur in the bridge if it were soldered or heated.

and thus annealed at the point of heat treating, which setting is eliminated in my construction by which perfect elasticity is obtained of the spring bridge throughout its 5 length.

While I have described certain construction forms which embody the principles of my invention, it is obvious that other desired changes in arrangement, may be made 10 within the spirit and the scope of the invention as defined in the appended claims.

I claim:

1. In an ophthalmic mounting, a pair of metallic lens rims, a sheet metal sleeve member secured to each of said rims of relatively soft sheet stock, a bridge member of relatively hard resilient stock for connecting said rims and having recesses in its opposite ends and located in said sleeve members said sleeve members being provided with depressions in their outer surfaces and projections on their inner surfaces enter the recesses in the bridge member to maintain said members in assembled relation.
2. In an ophthalmic mounting, a pair of sheet metal lens rims, a sheet metal sleeve member secured to each of said rims and of relatively soft sheet stock, a bridge member of relatively hard resilient stock for connecting said rims and having holes in its opposite ends and located in said sleeve members each rim and sleeve member being provided with depressions in one surface and projections on the opposite surface 30 to extend through the holes in the bridge members to maintain said members in assembled relation.
3. The method of securing a bridge to an ophthalmic rim without the use of heat, 40 which consists in securing a sleeve of relatively soft stock to the rim forming a recess in the end of the bridge and inserting the recessed end of the bridge in said sleeve and deflecting the stock of said sleeve to form a projection entering into said recess to secure the parts together.
4. The method of securing a bridge of relatively hard resilient spring metal to a metal ophthalmic rim without the use of heat, 50 which consists in securing a sleeve of relatively soft stock to the rim forming a recess in the end of the bridge and inserting the recessed end of the bridge in said sleeve and deflecting the stock of said rim and sleeve to cause the stock of said sleeve to move through said hole to secure the parts together.

move into said recess to secure the parts together.

5. The method of securing a bridge to an ophthalmic rim without the use of heat, 70 which consists in securing a sleeve of relatively soft stock to the rim, forming a hole in the end of the bridge and inserting the end of the bridge in said sleeve and deflecting the stock of said sleeve to form a projection entering into said hole to secure the parts together.

6. The method of securing a bridge of relatively hard resilient spring metal to a metal ophthalmic rim without the use of heat, 80 which consists in securing a sleeve of relatively soft stock to the rim forming a hole in the end of the bridge and inserting the end of the bridge in said sleeve and deflecting the stock of said rim and sleeve to cause the stock of said sleeve to move 85 through said hole to secure the parts together.

7. The method of securing a bridge to an ophthalmic rim, which consists in soldering a sleeve of relatively soft metallic stock 90 to the rim, forming a recess in the end of the bridge and inserting the recessed end of the bridge in said sleeve and deflecting the stock of said sleeve to form a projection entering into said recess to secure the parts 95 together.

8. In an ophthalmic mounting, a pair of lens rims, a sleeve member of sheet material secured to each of said rims, a bridge member for connecting said rims and having recesses in its opposite ends and located in said sleeve member, each sleeve member being provided with a depression in its outer surface in registry with a projection 100 on its inner surface, said projection entering the recess in the bridge member to maintain said members in assembled relation.

9. In an ophthalmic mounting, a pair of lens rims, a sheet metal sleeve member secured to each rim, a bridge member for connecting said rims and having a hole in one of its ends and located in said sleeve member, each sleeve member being provided with a depression in its outer surface in registry with a projection on its inner surface, said projection extending through the hole in the bridge member to maintain said members in assembled relation.

JOHN FIELDING. 120
